UNITED STATES PATENT OFFICE.

HENRY A. FROST, OF NEW YORK, N. Y.

DESIGN FOR A PULLEY-CASE.

SPECIFICATION forming part of Design No. 32,394, dated March 27, 1900.

Application filed March 2, 1900. Serial No. 7,131. Term of patent 14 years.

To all whom it may concern:

Be it known that I, HENRY A. FROST, a citizen of the United States, and a resident of the city of New York, borough of Manhattan, in the county and State of New York, have invented and produced a new and original Design for a Pulley-Case, of which the following is a specification, reference being had to the accompanying drawings, forming a part there-
of, in which—

Figure 1 is a perspective view of a pulley-case embodying the features of my design, and Fig. 2 is a front elevation of the said case.

The design consists in flat cheek-pieces 10, which are more or less convexed at their front faces, and the cheek-pieces are provided with interlocking members 11 at top and bottom.

The cheek-pieces at the rear are connected by a loop 12, which loop is near the central portion of the rear end of the cheek-pieces 20 and appears continuous with both.

Having thus described my invention, I claim as new and desire to secure by Letters Patent—

The design for a pulley-case, as herein 25 shown and described.

In testimony whereof I have signed my name to this specification in the presence of two subscribing witnesses.

HENRY A. FROST.

Witnesses:

J. FRED. ACKER,
JNO. M. RITTER.
